UNITED STATES PATENT OFFICE.

ANTIME MOTTEAU, OF BUENOS AIRES, ARGENTINA.

METALLIC CURTAIN.

1,374,514.

Specification of Letters Patent. Patented Apr. 12, 1921.

Application filed August 10, 1918. Serial No. 249,263.

To all whom it may concern:

Be it known that I, ANTIME MOTTEAU, citizen of the French Republic, residing at No. 1260 Garay street, Buenos Aires, Argentina, have invented certain new and useful Improvements in Metallic Curtains, of which the following is a specification.

This invention relates to certain new and useful improvements in metallic curtains 10 and especially in metallic curtains of the type which are capable of being wound up around an axis and its object is to provide for a metallic curtain of a simple and economical construction, which is of a very 15 light weight and which possesses many advantages over the heretofore known types.

The invention has also for its object to provide special means for the articulate connection of the slats, said means allowing or 20 not, according to circumstances, a certain free play between the adjacent slats.

A further object of my invention consists in the provision of means to avoid oxidation 25 of the edges of the slats, due to the friction of one against the other during the operation of the curtain.

Another object of the present invention is to provide an improved form of slat, by 30 which I obtain a maximum of resistance without increasing the thickness of the walls 35 of the slat.

This invention has also in view the provision of means by which the curtain may be used as a fire protective curtain.

This invention has still other objects in view which will appear from the following 35 specification and which will be hereinafter specifically claimed.

In order that my invention may be clearly 40 understood and easily carried into practice, reference will be made now to the accompanying drawings showing several embodiments of the invention, and by way of example.

45 In the said drawings,

Figure 1 is a front view of a metallic curtain according to my present invention, in its closed position.

Fig. 2 shows the same curtain partly 50 opened or wound up.

In both figures only a vertical side portion of the curtain has been illustrated.

Fig. 3 shows on an enlarged scale a front view of the side end of one of the slats.

55 Fig. 4 is a top view of the said slat.

Fig. 5 is a view corresponding to Fig. 3

of an alternative construction of the end of the slat.

Fig. 6 is a top view of the same.

Fig. 7 shows on an enlarged scale a vertical cross section through two of the adjacent slats, in which special connection means in the form of a hinge may be seen.

Fig. 8 is a front view of one of the hinges as used according to the present invention.

Fig. 9 is an edge view of the same.

Fig. 10 is a front view of an alternative form of hinge.

Fig. 11 is an edge view of the same.

Fig. 12 is a front view of another form of hinge.

Fig. 13 is an edge view of the same.

Fig. 13^a shows the loop of a slat, partly broken away and with a hinge according to Figs. 12 and 13 in position.

Fig. 14 is a plan view of a protective eyelet for the aperture in the loop of the slat.

Fig. 15 shows a preferred form of protective eyelet before being bent in position.

Fig. 16 is a central longitudinal section 80 through the loop of the slat, showing the eyelet of Fig. 15 partly in position.

Fig. 17 is a similar view with the eyelet in position.

Fig. 18 is a plan view of a protective sheet 85 for the free edges of the slat.

Fig. 19 is a similar view to Fig. 7 in which an alternative connecting means is employed.

Fig. 20 shows another embodiment of the 90 invention in which the hinges have been substituted by a continuous strap or band and where a constant space for air and light is left between each two slats.

Fig. 21 shows a modification of Fig. 20 95 in which special means are provided in order that the curtain may be used as a fire protective screen.

Similar characters of reference indicate same or like parts throughout the said 100

It must be clearly understood that although special reference has been made in the drawings and will be made in the following description to that type of metallic 105 curtains which are capable of being rolled up, the invention may be also applied to all other types of curtains without departing from the scope of the invention as herein-after claimed.

According to the invention the metallic curtain is formed of a series of slats 1 which

are conveniently connected with each other. Each of the said slats is constituted by a metal sheet bent in an **U**-shape, with the loop of the **U** at the upper end and the 5 free edges downward. In order to give to the said slats a maximum of resistance, without materially increasing the thickness of the sheet, it has been found that ribs must be formed on the surface of the said slat, 10 but such ribs must not protrude outward on account of the friction that would be set up and due to the fact that in these circumstances the coat of paint would fall and facilitate in this way the oxidation of the 15 metal sheet. Therefore I have found it more convenient to form along the slat a series of channeled longitudinal grooves 2, 2', 2^a, 2^{a'}, which are preferably symmetrical in order that they may oppose each other when the 20 metal sheet has been bent into the **U**-shape, as may be seen from the accompanying drawings. The metal sheet, previous to its bending, is metallized or coated with paint on both faces, so that, there being no friction 25 between the slats, the sheet may be kept free from oxidation.

Once bent into the **U**-shape, bent flat metal sheets 3 are introduced at the ends of each slat such sheets being used as a guide which 30 is capable of running between fixed guiding plates 4 mounted inside the frame 4', as shown in Figs. 3 and 4.

As shown in Figs. 5 and 6, the window or door frame 4' may be also used as a guide 35 for the ends of the slats, in which case plates 3 may be omitted or not.

The connection between the slats may take place in different ways, several of which have been shown by way of illustration.

40 One of the preferred forms consists in using as a connecting means a hinge which is fixed at one end to one of the slats, at any convenient point of the same, the butt end of the hinge being free to play within 45 the adjacent slat.

Figs. 8 and 9 show one of the systems of 50 hinges which may be used according to the present invention as a connecting means between two adjacent slats. The said hinge 50 consists of a metal sheet 5 which is bent in two and leaves a round space in the middle, said space tightly inclosing a butt 7. The butt 7 is mounted within the loop of a slat, through an orifice which is previously made 55 in the same, as may be seen from Fig. 7. The strap of the hinge is fixed at any convenient point of the upper slat 1, as for instance, by means of rivets 8 or the like. The butt 7 of the hinge is free to move within 60 the slat 1.

Figs. 10 and 11 show another form of hinge which is substantially like the one just described, but has at the sides of its 65 strap shoulders 6' which limit the movement of the hinge and are capable of resting

on the loop of the slat, around the orifice of same, or on the eyelet which protects the edges of the said orifice. In the manner shown no contact is possible between the free lower edges of each slat and the loop 70 of the adjacent one, and the fall of paint and consequent oxidation of the metal is avoided.

Another embodiment of hinge is shown in Figs. 12 and 13. This consists of a piece of 75 casting which is provided with side extensions 6'' replacing the shoulders 6' of the above embodiment. Said lateral extensions 6'' have a greater length than the upper aperture of the slat, so that they may rest 80 on the loop of the slat or on its eyelet when the curtain is in its lowermost position. Therefore, no direct contact between the slats is possible in this case.

In order that the edges of the upper orifice of the slat be protected against friction with the hinge and also from contact with the adjacent slat non-oxidizable metallic eyelets 10 may be welded or otherwise fixed to the said loop of the slat 1. Figs. 14 and 15 90 show two of the preferred forms of such eyelet. It consists of a metal sheet preferably of bronze or brass, in which according to the form represented in Fig. 14 two transverse cuts and a longitudinal cut have been 95 made. The tongues formed by these cuts are bent over the free edges of the orifice, as may be easily understood. The embodiment shown in Fig. 15 has two diagonally disposed cuts and it is particularly suitable 100 as it allows of covering all four edges of the orifice, as may be seen from Figs. 16 and 17.

When hinges according to Figs. 8 and 9 are used it is advisable to protect the lower free edges of the slats by means of a metal 105 sheet at the points where the hinges are used, as may be seen from Fig. 7. This protective sheet is shown in Fig. 18. It consists of a metal blank having a central body portion 11 with corresponding orifices for 110 the rivets 8 and two enlarged end portions 12 which are bent over the free edges of the slat. The metal sheet is bent and mounted on the hinge, as shown in the said Fig. 7.

Fig. 19 shows an alternative form of connection between the slats. The hinge 5 is substituted in this case by a single metal plate 16 which is fixed to a wing 13 formed by a bent up part of the orifice of the slat 120 loop, by means of a rivet 17. The said metal plate enters between the lower edges of the adjacent slat and is fixed to the same by means of a rivet 14, as may be seen from the said figure. The hole in the said plate 125 corresponding to the rivet 14 is elongated, so that the said plate may have a certain play with respect to the slat, so as to permit the rolling up and unrolling of the curtain. Said elongated orifice is shown in 15. 130

In the embodiment as shown in Fig. 20 all connecting hinges have been omitted and the slats are connected by means of a continuous metallic strip or band 16' running 5 from end to end through the curtain, in a vertical direction. A convenient number of said strips or bands may be used according to the size and to the weight of the said curtain.

10 The said bands or strips are fixed to the upper loops of the slats by means of rivets 17, in a similar manner to that shown in Fig. 19 and described with reference to the same and at the same time the strips are 15 also fixed at the central part of each of the slats by means of a second rivet 18, the strips or bands being provided with elongated orifices 19 for the said rivets in order to allow of the necessary play for the rolling up of the curtain.

20 The metallic curtain according to Fig. 20 may be used as an antifire curtain, as in the embodiment of Fig. 21. A small rope of asbestos or any like non-combustible material 20 is formed and fixed in any convenient manner in the space between each pair of adjacent slates. This together with the air chamber formed within each of the slats makes the curtain as a whole a very convenient anti-fire device.

25 In the embodiments shown in Figs. 20 and 21 the lower edges of each one of the slats may terminate in different horizontal planes, the outer edges being conveniently 30 lower, in order to avoid the entrance of rain or the like within the slats of the curtain, as may be easily understood. This is 35 specially desirable in this type of curtains where there is always a free space between the slats.

40 In the alternative constructions of Figs. 19, 20 and 21, the edges of the apertures in the loop of the slat may be protected by means of a sheet of a non-oxidizable metal, such as bronze, brass or the like, which has 45 been shown in two alternative embodiments at 21 and 22.

45 It is obvious that many changes and alterations may be introduced without departing from the scope of the present in-

vention. The slats, for instance, may be only a part of the curtain, the rest being constituted by an ordinary undulated sheet or the like.

Having now fully described and ascertained the nature of my said invention and in what manner the same is to be performed, I declare that what I claim is:

1. An all-metal curtain comprising a series of superposed U-shaped, sheet metal 60 links arranged with their loop portions upward, the sides of each link being formed at diametrically-opposite points with inwardly extending parts, and the loop of each link being formed with an aperture, 65 connecting means between the successive links arranged interiorly thereof and extending from each link through the aperture in the loop portion of the next lower link; and fastening devices inserted through 70 the said inwardly extending parts of the links and through the adjacent portions of said connecting means for securing the latter immediately to the sides of said links.

2. An all-metal curtain, comprising a series of superposed, U-shaped, sheet metal 75 links arranged with their loop portions upward, the sides of each link being formed at diametrically-opposite points with inwardly extending parts, and the loop of 80 each link being formed with an aperture, connecting means between the successive links arranged interiorly thereof and extending from each link through the aperture in the loop portion of the next lower 85 link; fastening means inserted through the said inwardly extending parts of the links and through the adjacent portions of said connecting means for securing the latter immediately to the sides of said links; 90 and protective means constructed of non-oxidizable sheet metal fitting conformably over and secured to the loop portion of each link and interposed between the opposite faces of said connecting means and the adjacent edges of the next higher links, to 95 avoid oxidation due to frictional contact between said links and said connecting means.

In testimony whereof I affix my signature.

ANTIME MOTTEAU.
